UNITED STATES PATENT OFFICE.

WILLIAM S. HADAWAY, JR., OF NEW ROCHELLE, NEW YORK.

ELECTRIC STOVE OR FURNACE.

1,406,851.

Specification of Letters Patent. Patented Feb. 14, 1922.

Application filed March 4, 1916. Serial No. 82,068.

To all whom it may concern:

Be it known that I, WILLIAM S. HADAWAY, Jr., a citizen of the United States of America, and a resident of New Rochelle, Westchester County, and State of New York, have invented certain new and useful Improvements in Electric Stoves or Furnaces, of which the following is a specification, reference being had to the accompanying 10 drawings, forming a part thereof.

My invention relates to heating apparatus and particularly to stoves for cooking, boiling water and the like, and to furnaces for melting precious metals, such as gold or 15 platinum.

One object of my invention is to provide a heating device in which the temperature of the heat is built up by successive steps from a low level to a higher level.

20 Another object is to provide a heating device in which steam or some other suitable vapor is utilized as a heat vehicle.

Another object is to provide a stove in which the heat is built up by successive steps 25 from a lower level established by the initial temperature of the heat vehicle to a relatively high level which may be regulated to accommodate the work for which the stove is intended and which is ultimately 30 determined by the dissociation of vapor which constitutes the heat vehicle.

Another object is to provide a plurality 35 of heating elements, a kinetic means for preventing loss of heat therefrom that shall constitute a suitable heat vehicle for transferring the useful heat to the working member, and shall furthermore constitute means for establishing a minimum heat level from which the heating elements may boost the 40 temperature in successive steps to the working level desired.

Still another object of my invention is to provide a stove or furnace that shall be adapted to receive low pressure steam from 45 any suitable generator and shall comprise a series of electric heaters which are protected against loss of heat by the steam and which serves to increase the temperature of the steam by successive stages, and a high

50 temperature dissociator heater which shall deliver useful heat at a very high temperature not only by radiation, convection and conduction, but also by chemical combination.

55 Other objects of my invention will be set

forth hereinafter, and in order that my invention may be thoroughly understood I will now proceed to describe the same in the following specification and then point out the novel features thereof in appended claims. 60

Referring to the drawings:

Figure 1 is a sectional elevation of a stove or furnace arranged and constructed in accordance with my invention.

Figures 2, 3 and 4 are sectional plan views 65 taken respectively on the line 2-2, 3-3 and 4-4 of Figure 1.

Figure 5 is a sectional elevation corresponding to Figure 1 and showing the upper portion of the stove with the crucible 70 removed and a condensation hood introduced so that it is adapted for cooking and other operations which do not require the high temperatures produced in the crucible.

Figure 6 is a diagrammatic view showing 75 the electric circuit connections for the apparatus shown in the previous figures.

The embodiment of my invention which is illustrated in Figures 1 to 4 inclusive, comprises a receptacle or box 10 having an outer 80 member 11, and an inner member 12, a plurality of vapor heaters 13 and 14 and a pot 15 having a dissociator heater 16 therein.

The inner member of the receptacle fits into the outer member and has an annular 85 notch 17 to receive a flange 18 of the pot 15, the crucible suspended within the mouth of the inner member of the receptacle. The pot is provided with a ledge 19 which is adapted to support a melting pot or inner 90 crucible 20. The melting crucible has a plurality of downwardly extending lugs or projections 21 and a lid 22. The complete device is provided with a cover 23 having a downwardly extending projection 24 which 95 fits into the opening of the pot 15.

The inner and outer members of the receptacle 10 are similar to each other and each of them comprises an outer shell 25, an inner shell 26, and interposed heat insulation designated 27. A vapor inlet pipe 28 extends through the bottom of the receptacle 10 and is adapted to supply vapor such as steam to the interior thereof. 100

The vapor heaters 13 and 14 are mounted 105 within the receptacle upon ledges 29-30 and constitute partitions so that they divide the interior of the receptacle into a plurality of chambers or compartments 31-32-33. The vapor from the pipe 28 is supplied to the 110

compartment 31 and as hereinafter explained, passes through the vapor heaters 13 and 14 in succession before it reaches the compartment 33.

- 5 The vapor heaters are similar to each other and only one will be described in detail. For example, the heater 13 comprises a body of porous material such as porous fire-clay, in which are imbedded electric 10 heaters elements 34. These elements may have the form of grids as shown in Figure 4, with their terminals extending through insulating plugs 35 in the inner casing 26 of the member 12 into a terminal pocket 36. 15 The terminal pockets of the heaters 13 and 14 are connected by a conduit 37 and the upper one is connected by conduit 38 to a terminal block 39 of the device.

The vapor heaters may correspond to those 20 set forth and described in my copending application Serial No. 82070, filed of even date herewith, their structures being such as to permit the steam to flow through them slowly, the heat generated in the electrical 25 elements being given up to the steam as it passes through the body.

It is evident that the pot with the melting 30 crucible may be removed and the device utilized as a stove or cooker by suspending cooking vessels within the chamber 33, condensation being allowed to escape through the outlet pipe 40 as hereinafter explained.

The dissociation heater 16 with which 35 the pot 15 is provided, extends transversely through it at a short distance above the bottom. It consists of a tube preferably in the form of a fulgurite and made of oxides of magnesia or some similar substance which may be operated at a glowing temperature 40 and which is a conductor of electricity when hot. Electric energy is supplied to this tube, suitable connections being made to the terminals 41 and 42. The tube is perforated to permit the hot vapor and gases to escape 45 within the pot and to transfer heat to the melting crucible.

In operation, when the pot is in place 50 the fulgurite tube is connected in circuit, as shown in Figure 6 of the drawings, but as it is a non-conductor at ordinary temperatures, there is no energy supplied to it. When the heaters 13 and 14 are active the vapor is delivered to the chamber 33 at a 55 high temperature. This vapor escapes into the pot through the perforations of the tube 16 and at the same time heats the tube sufficiently to permit the flow of electricity through the tube. The electricity traversing the tube soon heats it to a glowing temperature 60 especially as an atmosphere of high temperature steam surrounds it and prevents the loss of heat.

Heat is then radiated from the tube to 65 the melting crucible and is furthermore conducted to the crucible by the projections 21.

Heat is also transferred by convection, the hot gases and vapors flowing from the tube to the crucible. Furthermore, the temperature of the glowing tube is sufficiently high to dissociate the vapor, breaking it up into 70 its constituent elements, viz., hydrogen and oxygen. This dissociation takes up heat and serves as an automatic means for preventing an indefinite increase in the temperature of the tube. The gases produced by dissociation, are united by combustion as they rise in the pot and come against the melting crucible, on account of the reduction in temperature thus effected. In uniting by combustion they give off heat at high temperature 75 and while it is difficult to attribute any specific proportion of the heat transferred to the melting pot to any one of the four methods of heat transfer above outlined, it is certain that these methods are combined 80 and cooperate in producing very intense heat within the crucible.

The melting crucible will ordinarily be formed of some heat-resisting material and may be suitably referred to as an inner crucible.

When it is desired to use the apparatus for cooking and other operations which do not require the intense heat produced within the pot, the pot may be removed, as a whole, or omitted, and a cooking vessel such as 43 (Figure 5), may be suspended within the mouth of the chamber 33, above the vapor heater 14. The heat will be transferred to the cooking vessel very rapidly, but there will always be a certain amount of condensation when the vapor comes in contact with the surfaces of the vessel 43. In order to prevent the condensation water from dropping onto the vapor heater 14, I 100 prefer to utilize a condensation hood or deflector 44 composed of a plurality of overhanging rings which are spaced a short distance apart so as to permit the vapor to pass upwardly through it without difficulty while it effectively constitutes a shed for deflecting the condensation water into a trough 45. This is formed by a ring 46 and is adapted to discharge the water accumulated therein 105 through the outlet pipe 40.

While in the structure of Figure 1, I have shown two vapor heaters and a dissociator heater, my invention is not restricted to any specific number or arrangement of units and the number of vapor heaters may be increased indefinitely, depending upon the temperature desired, or only a single one may be employed instead of two. For example, several heaters constructed in accordance with my present invention may be embodied in a range such as shown and described in my copending application Serial No. 82,069 filed of even date herewith. In this case one of them may be provided with a single vapor heater to adapt it for low 110 115 120 125 130

temperature cooking, while another may have two and another three or more, for example.

The vapor heaters serve to increase the 5 temperature of the vapor step by step as already explained, and when used with the crucible they are arranged and adapted to provide a vapor temperature sufficient to heat the dissociator heater or glower to a 10 current-conducting temperature.

When the glower is thus heated and the electric current begins to flow directly through it, its temperature will immediately rise to a very high value and it will there- 15 after be immaterial whether the vapor supplied to it is maintained at the relatively high temperature previously acquired, or not. It is therefore advantageous to provide means for interrupting the supply of energy 20 to some or all of the vapor heaters after the glower is active. The circuit connections are clearly set forth in Figure 6 to which reference may now be had.

50 designates a source of electric energy; 25 51 a line switch, and 52 an automatic circuit breaker having stationary contacts 53 and a movable contact 54.

Assuming that the circuit breaker is closed, as shown, and that the line switch 51 30 is closed to admit energy to the vapor heaters, circuit is established from the source 50, through switch 51, conductor 55, vapor heater 14, conductor 56, vapor heater 13, conductor 57, circuit breaker 52 and conductor 35 58 to the opposite side of the line. A branch circuit is established from an intermediate point 59 in the vapor heater 14 through conductor 60, glower 16, conductor 61, release coil 62 of the circuit breaker 52 40 and conductor 58, circuit being completed as before. No current traverses this branch until the glower has been heated to a predetermined temperature which renders it a conductor. It then begins to take energy from the 45 line and the coil 62 is energized. When this coil is energized it trips a latch 63 permitting the circuit breaker 52 to be thrown open by a spring 64. Thus the branch circuit including the vapor heaters 14 and 13, is in- 50 terrupted but the glower branch is undisturbed so that energy is supplied to one section of the vapor heater 14 which acts as a ballast to steady the current traversing the glower.

55 The energized section of the vapor heater is active in boosting the temperature of the steam before it is delivered to the glower, but obviously the steam is supplied to the glower at a lower temperature than at first. The 60 glower, however, is capable of raising the temperature of the steam to the point of dissociation and the steam reacts beneficially in preventing the glower temperature from exceeding a safe value.

65 When a plurality of vapor heaters are em-

ployed, either with or without the glower, they may be connected in circuit in various ways to obtain a heat regulation; for example, they may be connected in series relation or in series multiple, or all of them may be 70 connected directly across the circuit.

While the receptacles 11-12 in the vapor heaters are shown as having a square section, they may of course, be cylindrical and various other modifications may be effected 75 within the spirit and scope of my invention. I therefore intend that only such limitations be imposed as are indicated in the appended claims.

What I claim is:

1. A heating apparatus comprising a receptacle having a working chamber adapted to receive a body to be heated, vapor heaters in the receptacle providing a plurality of successive chambers of which the working 85 chamber is the last, and means for introducing vapor into the first chamber of the succession, whereby the vapor is heated in successive stages by the vapor heaters and is delivered to the working chamber at high 90 temperatures.

2. A heating apparatus comprising a receptacle, means for admitting vapor into the bottom of the receptacle, a plurality of vapor heaters spaced apart within the receptacle 95 and dividing the space into a plurality of chambers, and a condensation outlet in the chamber farthest from the inlet.

3. A heating apparatus comprising a receptacle having heat insulated walls, a plurality of spaced vapor heaters constituting transverse partitions and subdividing the interior receptacle into a plurality of chambers of which one is a working space and is adapted to receive a body to be heated, each 100 of said vapor heaters being adapted to permit the vapor to flow slowly from one chamber to another and to impart heat to the vapor as it passes therethrough, so that it is finally delivered at high temperatures to the 105 working chamber.

4. A heating apparatus comprising a receptacle having heat insulated walls, a plurality of spaced vapor heaters constituting transverse partitions and subdividing the 110 interior receptacle into a plurality of chambers, each of said vapor heaters comprising a porous body through which the vapor may flow slowly, and electric heaters for imparting heat to the vapor as it passes through the 115 body.

5. A heating apparatus comprising a receptacle having a plurality of porous partitions each having relatively large heat capacity, electric heating elements disposed in 120 said partitions, and a glower in the upper chamber of the receptacle adapted to be initially energized by the heated vapor from the chamber below.

6. A heating apparatus comprising a re- 125

ceptacle, means for supplying vapor to the receptacle, a pot suspended in the mouth of the receptacle, a glower near the bottom of the pot, means for supplying electric energy to the glower, said glower being initially heated by the vapor in the receptacle.

7. A heating apparatus comprising a receptacle, means for supplying hot vapor to the receptacle, a glower which is a non-conductor at ordinary temperatures, means for supplying electric energy to the glower, said glower being initially energized by the vapor.

8. A heating apparatus comprising a receptacle, means for supplying hot vapor to the receptacle, a pot suspended in the mouth of the receptacle, a transverse tubular glower near the bottom of the pot, and means for supplying electric energy to the glower, whereby the glower is initially heated by the vapor and then serves to increase the temperature of the vapor.

9. A heating apparatus comprising a glower non-conducting at ordinary temperatures, a source of electric energy connected thereto, and means for admitting a heating medium to the glower whereby the temperature of the glower is raised, the glower is rendered a conductor and is heated to a high temperature by the electric energy in the heating medium.

10. A heating apparatus comprising a glower non-conducting at ordinary temperatures, a source of electric energy connected thereto, and means for admitting hot vapor to the glower whereby the temperature of the glower is raised, the glower is rendered a conductor and is heated to a high temperature by the electric energy in a high temperature atmosphere of vapor, the temperature or the glower being limited by the dissociation of the vapor into its constituent elements.

11. The combination with a glower having a negative temperature coefficient of conductivity of an atmosphere of hot vapor for initiating the activity of the glower, the temperature of the glower being limited by the dissociation of the vapor into its constituent elements.

12. A heating apparatus comprising a container, means pervious to vapor for dividing the container into a plurality of chambers, means for passing vapor through the chambers in succession, and means associated with the pervious means for imparting heat to the vapor, whereby the temperature of the vapor in the successive chambers is varied in stages.

13. A heating apparatus comprising a container, means therein pervious to vapor for dividing the container into a plurality of chambers, means for passing vapor through the chambers in succession, and electric

heaters associated with the pervious means for imparting heat to the vapor, whereby the temperature of the vapor in the successive chambers is increased in stages.

14. A heater comprising a plurality of heat generators pervious to vapor and a vapor heating medium adapted to be successively subjected to the heat of the generators and finally to deliver useful heat at relatively high temperatures.

15. A heater comprising a plurality of heating elements one of which is adapted to give up heat to the work, and kinetic means for transferring the useful heat to the heating elements in successive steps whereby the working element is maintained at a high temperature.

16. A heater comprising a plurality of electric heating elements, and kinetic means for preventing loss of heat from the heating elements and for transferring the useful heat from each of the electric heating elements to the next in successive steps.

17. A heater comprising an emitter of material which is a non-conductor of electricity when cold, means for supplying hot vapor thereto, and means for automatically supplying electric energy thereto when hot.

18. A heater comprising an emitter of material which is a non-conductor of electricity when cold, a vapor passage connected thereto embodying a series of chambers, means for supplying heat to the vapor to increase its temperature in the successive chambers, and means for supplying electric current to the emitter when it is heated to a predetermined temperature.

19. A heater comprising an emitter of material which is a non-conductor of electricity when cold, a vapor passage connected thereto embodying a series of chambers, means for supplying heat to the vapor to increase its temperature in the successive chambers, an electric control circuit including the emitter, and an electric circuit for supplying energy to the emitter in response to the energization of the control circuit.

20. A heater comprising a series of heating members and a working chamber, means for passing a heat transmitting medium through said members sequentially and into said working chamber, whereby said medium cumulatively absorbs heat from each of said members and relinquishes its heat to said working chamber.

21. A heater comprising a series of heating members, each composed of a mass pervious to vapor, electric means for generating heat in each mass, and a vapor for transferring heat from one of the pervious masses to the next and so on, whereby the temperature of the vapor is cumulative.

22. A heater comprising an emitter of material which is a non-conductor of electricity

when cold, means for supplying hot vapor thereto, and means for supplying electrical energy thereto when hot.

23. A heater comprising a series of electric heater elements of which the final heater of the series is adapted to give up its heat to the work, said heaters being so arranged as to permit a fluid medium to transfer heat from each heater to the next in the series, whereby the fluid medium is cumulatively heated and maintains the working element at a high temperature.

24. A heater comprising a series of spaced electric heater elements, one of said elements at one end of the series being adapted to impart its heat to the work and a receptacle containing the heaters so arranged as to permit a vapor heating medium to cumulate heat from the successive elements and transfer the heat so accumulated at high temperatures to the working element.

25. A heating apparatus comprising a receptacle, a porous vapor heater dividing the receptacle into a plurality of chambers, means for introducing a vapor directly into one of the chambers and through the vapor heater into the other, and a glower in one of said chambers adapted to be energized initially by the heated vapor.

26. A heating apparatus comprising a receptacle, a plurality of porous vapor heaters dividing the receptacle into a plurality of chambers, means for introducing a vapor directly into one of the chambers and through the vapor heaters into the others, and a glower in the final one of said chambers adapted to be energized initially by the heated vapor.

27. In a heating apparatus, a vapor heater comprising a resistance, means for connecting said resistance with a supply of electrical energy, a glower tube of material which is a non-conductor of electricity at

ordinary temperatures, but a conductor at higher temperatures, means for passing a vapor through said heater and then through the glower tube whereby the vapor heated by said resistance will raise the temperature of the glower tube to a degree at which it will conduct an electric current, means for supplying electrical energy to the tube, and means controlled by the current through the tube for controlling the current through the resistance.

28. In a heating apparatus, a vapor heater comprising a resistance, means for connecting said resistance with a supply of electrical energy, a glower tube of material which is a non-conductor of electricity at ordinary temperatures but a conductor at higher temperatures, means for passing a vapor through said heater and then through the glower tube whereby the vapor heated by said resistance will raise the temperature of the glower tube to a degree at which it will conduct an electric current, said tube being connected in series with a part of the resistance, and in multiple with another part thereof, and means actuated by the current passing through the glower tube for automatically breaking the circuit through that part of the resistance which is in multiple with the tube, when said tube current reaches a predetermined strength.

29. The combination with a plurality of separate heat generators and means for passing a heat transferring medium through said generators successively whereby the temperature of the medium is increased in stages; of a working chamber and means for discharging the heated medium into said working chamber.

In witness whereof, I have hereunto set my hand this 29 day of February, 1916.

WILLIAM S. HADAWAY, JR.
